(57) CLAIM

The ornamental design for a modular cosmetic organizer set as shown and described.

DESCRIPTION

FIG. 1 is an exploded perspective view showing my new design for a modular cosmetic organizer set;

FIG. 2 is a front perspective view thereof;

FIG. 3 is a front perspective view thereof, showing one of the containers moved out and in an open configuration;

FIG. 4 is a top plan view thereof;

FIG. 5 is a bottom plan view thereof;

FIG. 6 is a front elevation view thereof;

FIG. 7 is a back elevation view thereof;

FIG. 8 is a right side elevation view thereof;

FIG. 9 is a left side elevation view thereof;

FIG. 10 is a cross-sectional view of FIG. 6, taken along lines 10-10;

FIG. 11 is a cross-sectional view of FIG. 6, taken along lines 11-11;

FIG. 12 is a cross-sectional view of FIG. 4, taken along lines 12-12;

FIG. 13 is a cross-sectional view of FIG. 4, taken along lines 13-13;

FIG. 14 is a cross-sectional view of FIG. 6, taken along lines 14-14;

FIG. 15 is a cross-sectional view of FIG. 6, taken along lines 15-15;

FIG. 16 is a cross-sectional view of FIG. 6, taken along lines 16-16;

FIG. 17 is a cross-sectional view of FIG. 6, taken along lines 17-17;

FIG. 18 is a cross-sectional view of FIG. 6, taken along lines 18-18;

FIG. 19 is a cross-sectional view of FIG. 6, taken along lines 19-19;

FIG. 20 is an enlarged view of encircled area 20 in FIG. 10; and,

FIG. 21 is an enlarged view of encircled area 21 in FIG. 3.

The dotted lines shown in FIG. 1 depict brackets, to show the relationship and order of assembly of the modular cosmetic organizer set, and form no part of the claimed design. The unevenly dashed broken lines shown in FIGS. 3, 10, 20, and 21 encircle portions of the claimed design that are illustrated in enlargements and form no part of the claimed design. The unevenly dashed broken lines shown in FIGS. 4 and 6 depict the planes of the sectional views shown in FIGS. 10-19, and form no part of the claimed design.

1 Claim, 21 Drawing Sheets
